UNITED STATES PATENT OFFICE.

SILAS F. WOODWORTH, OF CLIPPER GAP, CALIFORNIA.

APPARATUS FOR AUTOMATICALLY APPLYING CAR-BRAKES.

SPECIFICATION forming part of Letters Patent No. 653,634, dated July 10, 1900.

Application filed November 11, 1899. Serial No. 736,720. (No model.)

To all whom it may concern:

Be it known that I, SILAS F. WOODWORTH, a citizen of the United States, residing at Clipper Gap, in the county of Placer and State 5 of California, have invented a new and useful Apparatus for Automatically Applying Car-Brakes, of which the following is a specification.

My invention relates to an improvement in devices having for their object the applying automatically of air-brakes in emergencies involving the derailment of a truck or part of a truck. I attain this object by mechanism illustrated in the annexed drawings, in which—

15 Figure 1 is a top view, and Fig. 2 a side view, of so much of a pilot-truck of a locomotive as is necessary to show my apparatus; and Fig. 3 is a detail view from in front of the cutting device which cuts the air-tube, 20 reducing pressure in the train-pipe, and applies the brakes.

Similar numbers refer to similar parts throughout the several views.

It is obvious that the drawings of the apparatus as applied to the pilot-truck, having its wheels outside of the bearings or boxes, would require some change in adapting it to a twelve-wheel passenger-coach or an eight-wheel freight-car, whose wheels are inside of 30 the boxes; but this may readily be done without abandoning the broad principles of the invention.

To the train-pipe 1 is fitted a small male T. To this male T is connected the flexible tube 35 or hose 3. This hose 3 (after several turns around the train-pipe) passes right and left to the cutting device, Fig. 3, and after passing through the shearing-bar 5 is plugged tightly in the fixed jaw or bracket 4, as shown, 40 Fig. 3, by the taper plug 8, thus making it both air-tight and secure by the simplest of means. The cutting device, Fig. 3, is bolted to the equalizing-bar 9 just back of the forward wheels, and in case of derailment as 45 one flange climbs the rail and drops down outside the opposite wheel will drop inside of the other rail, thus bringing its cutting-bar 5 in contact with the rail, cutting the wood pins 6 and the air-hose 3, whereupon 50 the air will escape from the cut end of the air-hose and all the brakes of the train will

be instantly applied. The bracket 4 is cored out, as shown by dotted lines, Fig. 2, thus permitting the movable jaw 5 to shear off the pins 6 and the tube 3 whenever its lower end 55 meets with any obstruction—such, for instance, as the ties or ballast between them—during the forward or backward movement of the train, so that were it to miss the rail entirely it still remains effective as adapted 60 to a locomotive.

I have chosen to locate the cutter-bar 5 inside of a vertical line from the rail-crown for the reason that when going upon and leaving a turn-table the ends of the table will settle 65 so much below the level of the converging and diverging tracks that were the bar 5 placed in line with the wheels directly over the rail-crown this settling of the table ends would cause contact with the rail unless the 70 cutter 5 were fixed at so great a height as to lessen or destroy its efficiency. With passenger or freight cars (which never cross a turn-table) the cutting-bar 5 may be fixed above the rail in line with the wheels. 75

I am aware that prior to my invention apparatus for automatically applying car-brakes were known as follows: first, by opening a valve in the train-pipe by means of connecting said valve or cock (by means of rods, 80 arms, rocker-shafts, and links) to levers or shoes adapted to contact with the rail; second, by frangible sockets connected with the train-pipe and arranged with reference to some part of the car or its trucks or with an 85 adjacent car, so as to be broken by the irregular motion resulting from derailment, and, third, by a frangible socket connected with the train-pipe and arranged to be broken or crushed by a lever actuated by mechanism 90 taking its movement from elevations or inclined planes placed adjacent to the rail and arranged to be elevated into an inclined position automatically by the opening of a drawbridge, switch, or semaphore. Therefore I 95 do not claim, broadly, the principle of automatically opening the air-pipe, but confine my claims to the simple air-hose and shear arranged to contact with the rail or substructure at any point a derailment may occur. 100

I claim as my invention—

1. In an apparatus for automatically apply-

ing car-brakes, the cutting device consisting of a fixed part 4 and movable part 5 arranged with relation to the rail and its substructure and adapted to sever the flexible tube substantially as shown for the purpose set forth.

2. In an apparatus for automatically applying car-brakes, the combination of the mov-

able cutter the fixed part 4 and the flexible tube 3 all substantially as, and for the purpose specified and shown.

SILAS F. WOODWORTH.
